UNITED STATES PATENT OFFICE.

HENRY H. MERCER, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

STONEWORKING-MACHINE.

1,149,075.

Specification of Letters Patent.

Patented Aug. 3, 1915.

Application filed February 1, 1909. Serial No. 475,366.

To all whom it may concern:

Be it known that I, HENRY H. MERCER, a citizen of the United States, and residing at Claremont, in the county of Sullivan and 5 State of New Hampshire, have invented an Improvement in Stoneworking-Machines, of which the following description, in connection with the accompanying drawings, is a specification, like letters on the drawings 10 representing like parts.

My invention relates to stone working machines, being more particularly, though not exclusively, intended for the improvement in the efficiency of power-driven truck 15 channelers or the like.

My invention will be best understood by reference to the following description when taken in connection with the accompanying illustration of one specific embodiment 20 thereof, while its scope will be more particularly pointed out in the appended claims.

In the drawings: Figure 1 is a side elevation, partially in section and partly broken away, showing a channeling machine embodying in one specific form certain features of my invention; Fig. 2 is a plan view, on a larger scale, partly in section of the quadrant support and clamping frame of the tool feed sprocket wheel; Fig. 3 is a 25 rear elevation, partly in section, showing the sprocket wheel support illustrated in Fig. 1; Fig. 4 is a plan view, partly broken away, showing the power transmission gearing for the channeling machine shown in 30 Fig. 1; Fig. 5 is a detail in side elevation showing one of the controlling levers; Fig. 35 6 is a section largely in plan but partly in elevation showing the power-transmission gearing; and, Fig. 7 is a detail in sectional 40 side elevation on the line 7—7 in Fig. 6.

Referring to the drawings and to the embodiment of my invention therein shown, I have disclosed for illustrative purposes a common form of track channeler having 45 usual features of construction which may be briefly referred to as follows. The channeler is provided with a main frame or carriage 1 mounted upon the usual truck wheels 2, the latter adapted to track upon the rails 3 ordinarily laid upon the quarry bottom. In the particular machine shown the truck 50 is propelled along the trackway under its own power, the motive means therefor being herein embodied in a truck driving en-

gine 4 to which pressure fluid, preferably in 55 the form of compressed air or steam, is led through the feed pipe 5.

For driving the truck, power is transmitted from the engine through the transverse transmission shaft 6 to the longitudinal driving shaft 7 near the opposite side of the truck by power transmission mechanism, which will be more fully described. The driving shaft 7 is mounted in bearings 8 upon the carriage and is provided at each 60 end with worms 9 meshing with underlying worm gears 10, the latter fixedly secured each upon one of the axles 11, which latter act to drive the truck wheels 2 secured at the end thereof.

As is usual in this class of apparatus, the cutting appliances are shown as mounted at the active or cutting side of the truck and comprise the tool or gang of tools 12 secured to the crosshead 13 and piston rod 14 and 65 adapted to be rapidly reciprocated by the actuating unit 15, herein in the form of a pressure fluid engine to which compressed air or steam is supplied from any suitable source by connections not herein shown.

For the guidance of the cross heads there are provided crosshead guides 16 which, together with the engine cylinder, are united into a unitary frame mounted for sliding adjustment upon suitable guideways 17 formed 85 on the upright standard 18, the latter secured at the side of the truck. The sliding frame is provided as usual with gib 19 which overlie the back of the standard guideways so that the entire frame, with the 90 tools and their actuating devices, may be adjustably advanced toward or retracted from the work.

The standard at its lower rear side is provided with one or more boxes or brackets 20 95 which are shaped to fit the longitudinal trunnion shaft 21, the latter secured at its ends by the cap pieces 22 to the frame or carriage. The standard may be clamped rigidly to the trunnion shaft at any desired 100 inclination, or at either end thereof, by means of the U-shaped clamping bolts 23 and the clamping nuts 24. The standard may be adjusted to different inclinations by loosening the clamping bolts and altering 105 the position and inclination of the standard, as desired, one or more lateral brace rods 25 and rear brace rods 26 being employed as

usual to brace or stay the upper part of the standard while the machine is cutting.

During the operation of the machine the channeler is advanced along the trackway, the tools acting to cut a channel groove of increasing depth. For adjustably feeding the tools with their actuating devices downward upon the standard to adapt them to the increasing depth of the cut, or for elevating the tools out of the cut, there is provided the feed screw 27, which herein is provided with collars 28 and 29, holding the screw against longitudinal displacement in the overhead arched piece 30 of the standard, but permitting turning movement thereof. The lower end of the screw is threaded and passes through a threaded member or nut 31, which is rigidly secured to a part of the engine cylinder casting so that the turning of the screw in one direction or the other retracts or advances the cylinder frame. For turning the screw the latter has secured to its upper end above the collar 29 the beveled gear 32 which meshes with the smaller beveled pinion 33 on the short shaft 34, the latter carrying on its outer end the sprocket wheel 35 adapted to be turned by the sprocket chain 36. The shaft 34 may be manually turned to feed the tools by means of the handle provided on the sprocket wheel, but, for feeding by power the chain passes down to the carriage frame where it is engaged by the driving sprocket wheel 37 to which power-actuated turning movement may be imparted for lowering or raising the tools, such movement being herein transmitted thereto from the engine 4 on the transmission shaft 6 through power transmission gearing to be more fully described.

Referring to the power transmission devices interposed between the engine and the truck-driving mechanism on the one hand and the tool feeding mechanism on the other, reference may be had to Fig. 4 and also more particularly to Fig. 6. From this it will be seen that the transmission shaft 6 carries fixedly secured to its outer end the beveled gear 38, the latter meshing with the two gear members 39 and 40, and acting to drive both of them at the same speed but in opposite directions.

Both gear or truck-driving members 39 and 40 are mounted to rotate loosely upon the countershaft 41, but may be clutched thereto, either one at will, to turn the same in either direction and thereby turn the pinion 42 keyed to the said shaft and meshing with the gear 43, the latter keyed to the truck-driving shaft 7.

Any suitable form of clutching means may be employed, but herein means are provided as follows; the construction being substantially the same for each clutch device so that one only need be described. Re-

ferring to the gear member 39, the same is provided with an outwardly extended drum-shaped portion 44 which is encircled by a split band 45 (see Fig. 7), which latter is provided at its separated ends with two outwardly turned lugs 46 and 47. The band is secured to a box or casing 48, which latter is keyed to the shaft 41, the band being adjustably held therein by means of an adjustable set screw 49 engaging one lug 46, and a band-actuating pin 50 engaging the other lug 47. The pin 50 is mounted to turn in the walls of a pocket 51 formed in said casing and presents a flat face 52 to the outer edge of said lug 47, so that, when turned, it acts to draw the separated ends of the band together and grip the drum member 44; thereby clutching the casing 48 to the gear member 39 and operatively connecting the countershaft 41 to the transmission shaft 6.

To turn the actuating pin 50, the latter is provided with the curved arm 53 which lies down and over the hub 54 of the casing, being pressed inwardly by means of the spiral spring 55. The arm 53, however, may be swung outwardly to turn the pin by means of the wedge-shaped sleeve 56 slidable lengthwise the hub 54. The sleeve is provided with a circumferential groove 57 with which engages a yoke-shaped arm 58 (Fig. 4), said arm being attached to the slide rod 59. The end of the slide rod (see Fig. 5) is secured to a hand lever 60 pivoted at 61 upon the frame, so that, by moving the hand lever, the gear member 39 may be clutched to or unclutched from the countershaft 41. The remaining gear member 40 is provided with clutching devices similar in construction to those already described, and its wedge-shaped controlling sleeve 62 is also adapted to be moved by an arm 63, the latter also connected to the slide rod 59, so that movement of the latter will serve to move both sleeves simultaneously. Preferably the slide rod and handle are so arranged that they may be moved to any one of three positions, one of which is effective to drive the truck in one direction, another in the opposite direction and a third or intermediate position for securing inaction or rest.

Referring now to the mechanism for varying the speed of the driving sprocket wheel 37 for the tool feed, the latter is journaled on a stud shaft 64 and has formed integrally therewith the beveled gear 65 which meshes with a similar gear 66 keyed to the sleeved driving member 67, the latter mounted for loose rotation on the driving shaft 7. For turning the driving member 67 in either direction at will, thereby to raise or lower the tools, the sleeve is provided at opposite ends with drum-shaped members 68 and 69 which may be clutched to or unclutched from oppositely driven driving members 70 and 71, respectively, by devices of a gen-

erally similar construction to those previously described.

The driving member 70 is provided with a spur gear 72 which meshes with spur teeth cut upon the gear or truck-driving member 39, while the tool feed driving member 71 is provided with spur teeth 73 which mesh with similar teeth cut on the truck-driving member 40. From this it follows that the driving members 70 and 71 are constantly driven in opposite directions so that, by clutching one or the other to drive the sprocket 37, as described, the tools may be raised or lowered.

As in the case of the clutching devices for the truck driving member, the tool feed driving member 70 is provided with an actuating pin 74 adapted to be turned through the arm 75 and the sliding sleeve 76 to cause the split band 77 to grip the drum 68. Similarly, through a like actuating pin and band the tool feed driving member 71 may be clamped to the drum 69 to turn the sprocket wheel in an opposite direction by sliding movement of the controlling sleeve 78. To shift the controlling sleeves simultaneously in either direction the sleeve 76 (see Fig. 4) is engaged by the arm 79 and the sleeve 78 by the arm 80, both arms being attached to the slide rod 81 adapted to be shifted by the hand lever 82, so that, through the movement of the latter by the connections described the feed screw may be turned in one direction or the other, or allowed to remain stationary.

It will be noted that the power-transmission gearing described provides two sets or pairs of driving members, one for the truck and the other for the tool feed, the members of each pair being driven in opposite directions whereby any one may be clutched to its respective driven shaft independently, whereby either tool feed driving member may be rendered operative for feeding the tool irrespective of the operative relation of the truck driving members. It therefore follows that the tool feed may be operated under power and in either direction whether the truck be in motion or at rest and irrespective of the direction in which it may be moving.

In adjusting the standard to different inclinations, the position of the driving sprocket wheel 37 should also be adjusted to conform thereto and for this purpose the shaft 64 on which the sprocket wheel is journaled is mounted in an adjustable frame or swinging quadrant 83, the latter adapted to be adjustably swung about the driving shaft 7 to keep the required relation between the beveled gears 65 and 66, while, at the same time, conforming to the inclination of the driving sprocket chain 36.

The quadrant 83 is provided with a split hanger bracket 84 by which it is secured to

swing about the shaft 7, such bracket also affording a support 85 for one end of the sprocket wheel shaft 64, the opposite end thereof being supported in a bracket 86. The quadrant 83 is provided with segmental 70 guiding edges 87 (Fig. 2), the sides of which are embraced by the walls 88 of a clamping frame 89 which, after the quadrant has been adjusted to the required position, is clamped tightly about the latter 75 to hold it fixedly in place.

The clamping frame is secured to the front wall 90 of the carriage frame by bolts 91 and comprises two projecting segmental ears which present the walls 88 to embrace 80 the quadrant, these being connected at their lower ends by the clamping bolt 92, and also the connecting portion 93 partly split at 94. The connecting portion 93 unites the upper ends of the segmental ears and 85 is adapted to be tightly clamped together by the clamping bolt 95.

The quadrant is provided with a pin 96 which abuts against a lug 97 on the frame 1 to limit the movement of the quadrant beyond a position corresponding to an upright position of the standard, such pin also limiting the movement in the opposite direction by engagement with the clamping bolt 92. When the standard is tipped back 95 the bolts 92 and 95 may be loosened and the quadrant tipped with it to any desired position, after which the clamping frame is again tightened by the clamping bolts 92 and 95.

As represented in Fig. 3, the standard is provided with a laterally adjustable guide roll or sheave 98 engaging one run of the sprocket chain, so that the latter may be guided and kept taut to the sprocket wheel 105 35 in whatever position on the truck the standard may be adjusted.

Since the quadrant and the clamping frame present coöperating extended segmental clamping and holding portions symmetrically arranged with reference to the axis of the sprocket wheel and on either side thereof, the sprocket wheel is securely held in its adjusted position against any lateral pull of the sprocket chain.

While I have herein shown and described one specific form of my invention for the sake of illustrating the general principles thereof, it is to be understood that the same is not limited to the details of construction, 120 or the form or relative arrangement of parts herein shown, but that extensive deviations may be made therefrom without departing from the spirit of the invention.

Having thus described my invention, what 125 I claim is:

1. In a track channeling machine, the combination with a truck, of a standard carrying cutting appliances at the side of the truck, adjustable connections between the 130

standard and the truck, means for feeding the cutting appliances toward or from the work including a flexible driving connection leading to the truck, a driving member on the truck engaging the same, and means for adjustably supporting said member on the truck to conform to the adjustments of said standard.

2. In a stone working machine, the combination with a support, of a frame carrying cutting appliances, adjustable connections between the frame and the support whereby the former may be adjusted at different angular inclinations, means for feeding the cutting appliances toward or from the work, said means including a flexible connection extending to the support, a driving member and means for adjustably holding said member on the support to conform to the adjustments of said frame.

3. In a stone working machine, the combination with a support, of a frame carrying cutting appliances, means for attaching said frame for swinging adjustment on the support, means for feeding the cutting appliances toward or from the work including a sprocket chain passing to the support, a driving sprocket wheel having a journal support, said support being mounted for swinging adjustment to correspond to the adjustment of said frame, and means for fixedly clamping said swinging support on each side of the axis of said sprocket wheel.

4. A stone working machine having a support, a frame carrying cutting appliances mounted for angular adjustment upon said support, tool feeding devices including a power-driven tool feed actuating member, a swinging quadrant acting as a support for the same, said quadrant having extended segmental clamping walls, and a clamping frame on said support adapted to embrace the segmental clamping walls of the quadrant and hold the same in fixed position.

5. A channeling machine having a truck, an adjustably mounted standard, cutting appliances, feeding devices for said cutting appliances, the latter including a drive shaft on the truck, a driving member driven from said driving shaft, a quadrant carrying said driving member and mounted to swing about said driving shaft, a clamping member adapted to clamp said quadrant and hold the same symmetrically with reference to the axis of the driving member.

6. In a channeling machine, the combination with a truck and standard, of cutting appliances and tool feeding devices, the driving sprocket 37, quadrant 83, drive shaft 7, and clamping member 89 adapted to clamp and hold fixed in its adjusted position the quadrant 83.

7. In a track channeling machine, the combination with a truck, of a standard car-

ried thereby, cutting appliances, feeding devices for said cutting appliances, motive means upon the truck, means to render said motive means operative for driving the truck in either direction or for rendering the same inoperative to drive the truck, and means irrespective of the power-actuated movement of the truck for rendering said motive means operative to feed the cutting appliances either toward or from the work.

8. A track channeling machine having cutting appliances, power-actuated means for driving the truck, and power-actuated means for feeding the cutting appliances either toward or from the work irrespective of the movements of the truck.

9. A channeling machine having a truck, a truck driving shaft, cutting appliances, a driving member for feeding said cutting appliances, separate pairs of power-actuated driving members, the members of each pair being driven in opposite directions, and means for connecting at will either member of one pair to the truck driving shaft, and either member of the other pair to the feeding member for the cutting appliances.

10. A track channeler having a truck, a motor thereon, means for connecting the motor to drive the truck in either direction, cutting appliances and means for connecting the motor to feed the cutting appliances toward or from the work simultaneously with the connection of the motor for driving the truck.

11. A track channeling machine having cutting appliances, power-actuated means for driving the truck and power-actuated means for feeding the cutting appliances either toward or from the work while driving the truck, irrespective of the movement of the truck.

12. In a track channeling machine, the combination with a truck of a standard carrying cutting appliances at the side of the truck, adjustable connections between the standard and the truck, means for feeding the cutting appliances toward or from the work including a flexible driving connection leading to the truck and a driving member on the truck engaging the same, means for adjustably supporting said member on the truck to conform to the adjustment of said standard, a truck driving motor and connections for actuating said driving member from said truck driving motor.

13. A track channeling machine having cutting appliances, a motor for driving the truck, a truck feeding mechanism, means for feeding the cutting appliances toward the work and independent connections including reversing devices between said motor and said truck driving mechanism on the one hand and said motor and feeding means on the other.

14. In a track channeling machine, the combination with a truck, a standard having cutting appliances, means adjustably supporting said standard for tipping movement at the side of the truck for adjustment of the angle of the cut, a truck driving motor, means for feeding cutting appliances toward the work and connections between the truck driving motor and the feeding means effective in the different positions of adjustment of the standard.
15. In a track channeling machine, the combination with a truck and truck driving mechanism, cutting appliances, tool feeding mechanism for feeding the cutting appliances toward the work, a common driving motor for said truck driving mechanism and said tool feeding mechanism, means for connecting said motor to or disconnecting the same from said tool feeding mechanism, and other means capable of independent operation for connecting

said motor to or disconnecting the same from said truck driving mechanism, whereby the truck driving mechanism and tool feeding mechanism may be operated by said motor independently or simultaneously. 25

16. In a track channeling machine the combination with a truck of a frame carrying cutting appliances, means for feeding the cutting appliances toward the work, truck driving means, connections for driving said truck driving means and said feeding means from said motor, and means for reversing the movement of each of said means independently of the reversing movement of the other. 30 35

In testimony whereof, I have signed my name to this specification in the presence of two subscribing witnesses.

HENRY H. MERCER.
